(57) **CLAIM**

The ornamental design for a set of elements of a wakeboard tower, as shown and described.

DESCRIPTION

FIG. 1 is a perspective illustration, from the front and right side, of a first embodiment of set of elements of the wakeboard tower according to my design;

FIG. 2 is a top view thereof;

FIG. 3 is a right side view thereof, the left side view being a mirror image of the right side view;

FIG. 4 is a front view thereof;

FIG. 5 is a rear view thereof;

FIG. 6 is a perspective illustration, from the front and right side, of a second embodiment of elements of the wakeboard tower according to my design;

FIG. 7 is a top view of FIG. 6;

FIG. 8 is a right side view of FIG. 6, the left side view being a mirror image of the right side view;

FIG. 9 is a front view of FIG. 6; and,

FIG. 10 is a rear view of FIG. 6.

Where included, broken lines showing environment or structure are for illustrative purposes only and form no part of the claimed design.

1 Claim, 6 Drawing Sheets
